US0D1078608S

(12) **United States Design Patent** (10) **Patent No.:** **US D1,078,608 S**
(45) **Date of Patent:** **** Jun. 10, 2025**

(54) **ENERGY STORAGE POWER SUPPLY**

(71) Applicant: **GUANGDONG PISEN ELECTRONICS CO., LTD.**, Shenzhen (CN)

(72) Inventors: **Wu Zhao**, Shenzhen (CN); **Yongchuan Zhang**, Shenzhen (CN)

(73) Assignee: **GUANGDONG PISEN ELECTRONICS CO., LTD.**, Shenzhen (CN)

(**) Term: **15 Years**

(21) Appl. No.: **29/888,565**

(22) Filed: **Apr. 2, 2023**

(51) LOC (15) Cl. **13-02**

(52) U.S. Cl.

USPC **D13/110**; D13/103

(58) **Field of Classification Search**

(57) **CLAIM**

The ornamental design for an energy storage power supply, as shown and described.

DESCRIPTION

FIG. 1 is a front, left and top side perspective view of an energy storage power supply, showing our new design; FIG. 2 is a rear, right and bottom side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown in the drawings represent portions of the energy storage power supply that form no part of the claimed design.

1 Claim, 8 Drawing Sheets
